UNITED STATES PATENT OFFICE.

ALBERT EDWARD WALKER, ARTHUR WALKER, AND GEORGE WALKER, OF NORWOOD GREEN, NEAR HALIFAX, ENGLAND.

SHUTTLE-BOX FOR ROTARY-BOX LOOMS.

No. 882,361.

Specification of Letters Patent.

Patented March 17, 1908.

Application filed October 23, 1905. Serial No. 284,029.

To all whom it may concern:

Be it known that we, ALBERT EDWARD WALKER, ARTHUR WALKER, and GEORGE WALKER, all subjects of the King of Great Britain, residing at Norwood Green, near Halifax, England, have invented a certain new and useful Improvement in Shuttle-Boxes for Rotary-Box Looms, of which the following is a specification.

10 The invention relates to the shuttle-boxes of rotary-box looms, and has reference to a novel and improved construction and mounting of the same which enables the shuttle-box, by the simplicity and strength of its 15 construction, to be applied to and work upon the loom with greater mechanical precision and efficiency than is possible with the usual construction of shuttle-box.

In the accompanying drawings: Figure 20 1, is a front elevation of a rotary shuttle-box constructed in accordance with this invention. Fig. 2, is an end elevation of same looked at from the direction of the arrow on Fig. 1. Fig. 3, is a section on line *a, b* of Fig. 25 1. Fig. 4, is an end view illustrating a slightly modified construction of box.

The axis of the shuttle-box is a square shaft 1 which forms the foundation for the bottom of each compartment in a shuttle-box of four compartments. To each side of 30 the shaft a metal plate 2 is secured by screws or the like 3 the series of plates being placed upon the shaft 1 successively in the same direction as shown.

35 Each plate 2 is common to two compartments forming on the outer side 4 of the plate the bottom of a compartment and on the inner side 5 the front wall of a compartment.

40 At the required distance from the front wall 5 of each compartment the swell 6 is mounted by being pivoted at its fulcrum end upon a stud 7 or the like firmly fixed on the plate 2 its free end 8 (Fig. 1) resting in a bracket-piece 9 or other suitable support secured to the plate 2. The swell is pressed inwardly by a flat spring 10 secured to the plate by a fixed pin 11 and a screw 12 and bent as shown at 13, at right angles to meet 45 the swell 6, or by other convenient means.

The bracket-piece 9 forms the entrance plate for the shuttle into the compartment and is shaped as, or has formed upon it at its outer end, an arc 14 to fit inside a flange 15 5 on a circular plate 16 carried by a bar 18

forming part of the box-supporting frame 22 which forms a cup-bearing in which the inner end of the shuttle-box rotates, the bearing 16 being cut away as shown at 17 opposite the shuttle-race.

60 The bottom 4 of each compartment is beveled as shown in Figs. 2 and 3 to suit the bevel of the shuttle-race, when the latter is not at a right angle with the reed. Suitable shuttle-retaining ledges 19 are provided for 65 each compartment, being formed upon the bracket pieces 9, which are secured to the plates 2.

An additional bar 25 such as is used with vertical boxes is employed connecting the 70 outer bracket with the going-part and acting as a stay for guiding the picker, and mounted in the present invention in such a position relatively to the picker spindle 26 that the picker 27 bears against it during its forward 75 and inward stroke so that the picker maintains a vertical position throughout the stroke. The picker fork 28 receives the picker after the stroke and maintains it in a vertical position while at rest.

80 In Fig. 4 the modified arrangement shows plates 2 in which the width of the sides of the square axial shaft 1 may be the full width of the compartment, the shaft being turned down between the securing points of the 85 plates to reduce its increased weight. In this construction the extension 2^a of the plate 2 beyond the shaft 1 may be arranged to form either the front or back of a compartment. In the latter case the front 5^a of the 90 compartment may be fixed upon the plate by a bracket 9 at each end, which brackets also carry the swell 6 of an adjoining compartment.

95 The shuttle-box is mounted at its inner end in a cup-bearing 15, 16 carried by the bar 18 of the box-supporting frame 22 as already stated, and at its outer end the shaft 1 is turned down and carried in a divided bearing 21 as shown in Fig. 1, the upper half 21^a 100 of the bearing being detachable and screwed upon the lower half 21^b which is fixed upon the box-supporting frame 22 or forms part of it. The corners of the unturned square shaft at each end of the divided bearing prevent lateral movement in the shuttle-box.

105 What we claim is:—

1. In shuttle boxes for rotary-box looms comprising several compartments, the combination of an axial shaft forming the foun- 110

dation for each compartment, bearings for said shaft, a series of plates secured to said shaft so that one side of each plate forms the bottom of a compartment, and part of the 5 other side of same plate forms the front wall of an adjoining compartment, a swell to each compartment and means for retaining the shuttle in each compartment, substantially as described.

10 2. In shuttle boxes for rotary-box looms comprising several compartments, the combination of an axial shaft forming the foundation for the shuttle box, bearings for said shaft, a series of plates secured to said shaft so that one side of a plate forms the bottom 15 of a compartment and part of the other side of the same plate forms the front wall of an adjoining compartment, a swell to each compartment, and supports having shuttle-retaining ledges for each compartment, substantially as described.

25 3. In shuttle boxes for rotary-box looms comprising several compartments, the combination of an axial shaft forming the foundation for each compartment, bearings for said shaft, a series of plates secured to said shaft so that each plate is common to two compartments, a swell for each compartment, and bracket pieces provided with shuttle retaining ledges secured to said plates for carrying said shuttle-retaining ledges, substantially as described.

35 4. In shuttle boxes for rotary-box looms comprising several compartments, the combination of an axial shaft, an end bearing for said shaft, a series of plates secured to said shaft so that each plate is common to two compartments, bracket pieces provided with shuttle retaining ledges and having arcs 40 formed thereon, and means for admitting a shuttle into a compartment, comprising a circular plate having an opening therein and a flange forming a cup bearing within which said arc-shaped bracket pieces are capable of 45 revolving, substantially as described.

5. In shuttle boxes for rotary-box looms, the combination of an axial shaft, a series of plates secured to said shaft so that each plate is common to two compartments, a

swell for each compartment, bracket pieces 50 secured to each plate within which the free ends of said swells rest, a spring secured to each plate for controlling the motion of the swells, said bracket pieces having shuttle-retaining ledges for each compartment, substantially as described.

6. In shuttle boxes for rotary-box looms, the combination of an axial shaft, bearings for said shaft, a series of plates secured to said shaft so that each plate is common to 60 two compartments, a swell for each compartment, bracket pieces carried by said plates against which the free ends of the swells rest, and having shuttle retaining ledges, substantially as described.

65 7. In shuttle boxes for rotary-box looms, comprising several compartments, the combination of a square axial shaft, bearings for said shaft, a series of plates secured to said shaft and forming compartments, the extensions of said plates forming the fronts of the compartments, bracket pieces secured to said plates and forming the entrances of said compartments, and a swell for each compartment carried by said brackets, substantially as described.

70 8. In shuttle boxes for rotary-box looms comprising several compartments, the combination of driving means, an axial shaft forming the foundation for each compartment, a series of plates secured to said shaft so that each plate is common to two compartments, end bearings for said shaft, a rotary-box supporting frame carrying said bearings, a picker and a bar connecting the outer part 85 of the box frame with the driving means and acting as a stay for said frame and as a guide for said picker, substantially as described.

85 In witness whereof we have hereunto set our hands in the presence of two subscribing 90 witnesses.
